Fig. 7

Fig. 8

FIG. 1 is a front perspective view of a combined stand and set of oriental temple blocks or similar article showing my new design;

FIG. 2 is a fragmentary rear elevational view to a reduced scale, a portion being omitted for convenience in illustration;

FIG. 3 is a fragmentary view showing the front of one of the blocks;

FIG. 4 is a fragmentary view showing the rear of one of the blocks;

FIG. 5 is a fragmentary view showing the top of one of the blocks;

FIG. 6 is a fragmentary view showing the bottom of one of the blocks;

FIG. 7 is a fragmentary view showing the right end of one of the blocks; and

FIG. 8 is a fragmentary view showing the left end of one of the blocks.

I claim:

The ornamental design for a combined stand and set of oriental temple blocks or similar article, as shown.
